ATTY.

UNITED STATES PATENT OFFICE.

ANTOINE J. LANGEIER, OF PROVIDENCE, RHODE ISLAND.

SWAGING-MACHINE.

SPECIFICATION forming part of Letters Patent No. 542,021, dated July 2, 1895.

Application filed January 21, 1895. Serial No. 535,699. (No model.)

To all whom it may concern:

Be it known that I, ANTOINE J. LANGEIER, a citizen of the United States, residing at Providence, in the State of Rhode Island, have invented a new and useful Improvement 5 in Swaging-Machines, of which the following is a specification.

My invention relates to the improved means employed to effect a closing or opening movement of the swaging-dies while the machine is in operation; and it consists in the employment of an adjustable toggle-link between the swaging-die and the roller-engaging block, as hereinafter fully set forth.

15 Figure 1 represents a front elevation of the machine with the face-plate removed. Fig. 2 represents a side elevation and partial section. Fig. 3 represents an enlarged transverse section. Fig. 4 represents an axial section, and Fig. 5 a side view, of the toggle-link which is interposed between the swaging-die and the roller-engaging block. Fig. 6 represents an enlarged detail view of the connecting-head, by means of which the toggle-link 25 is actuated to cause the opening or closing movement of the die.

In the drawings, A represents a stationary head, in which is journaled the die-holding spindle B, to which rotary motion is imparted 30 by means of the pulley C. The head A is provided with the beating-rollers a² a², which are adapted for engagement with the sliding blocks D D to cause the proper reciprocation of the dies E E, the said engaging blocks 35 and dies being loosely held in the diametrical groove j, made in the enlarged forward end of the holding-spindle B, and between the dies E E and the engaging blocks D D are placed the toggle-links F F, the said links 40 consisting of the block a, fitting in the cylindrical recess or socket b in the block D, and the block a', fitting in the recess or socket b' in the die E, the said blocks a and a' being connected to each other to form the toggle-link 45 by means of the cylindrical pin c, which fits into the cylindrically curved recess c' c', made in the adjacent sides of the blocks a and a', and the said blocks a and a' are secured to each other and to the pin c by 50 means of the washers d d, which are placed upon the projecting ends of the pin c, and are provided with the circular flange d', which en-

ters the circular grooves d² d², made in the ends of the blocks a and a' to receive the same, the parallel sides s of the said washers d 55 d being held in the recesses e e in the opposite sides of the opening f, made in the head g, Fig. 6, so that upon the movement of the said head g back and forth a corresponding movement will be imparted to the central joint of 60 the toggle-link F. The head g is provided with a shank h, which passes loosely through a perforation i, made in the die-holding spindle B, and is secured to the sliding sleeve G, the said sliding sleeve being provided with a 65 groove k, in which is placed the loose ring H, to which operative connection is made from a treadle by means of the toggle-jointed arms m m', the arm m being jointed to the ring H by means of the screw n and the arm m' jointed to 70 the bearing-standard o of the head A by means of the screw n' and to the middle joint n² is attached the downwardly-extending link p, which is connected with the treadle, the said link and treadle being caused to rise by means 75 of a spiral or other suitable spring q, and upon the downward movement of the treadle by the operator of the machine the sleeve G will be thrown forward, thus forcing forward the central joints of the toggle-links F F and changing their angular position, whereby the distance between the engaging blocks D D and the working faces of the dies E E will be increased, so that the dies at the impact of the beating-rollers a² a² will be brought nearer 85 together than before.

The several parts are held in position in the groove j of the die-holding spindle by means of the face-plate J, which is secured to the front face of the spindle B by means of 90 screws. When the axes of the blocks a a' and the pin c are in the same right line, as shown in Fig. 3, the dies will be carried to their extreme inward position, and the toggle-links will transmit the impulse received 95 from the beating-rollers to the dies without lateral thrust, and a uniform beating distance will be attained at the completion of the closing movement of the dies upon the work, which is an important feature.

I claim as my invention—

1. In a swaging machine, the combination of the rotating head, the beaters, the swaging dies, and the engaging blocks, with the inter-

mediate toggle-links, and means for changing the angle of the toggle-links while the machine is in operation, substantially as described.

5. 2. In a swaging machine, the combination of the rotating head, the beaters, the swaging dies, and the engaging blocks, with the intermediate toggle-links, and the slidable heads for changing the angle of the toggle-links, while the machine is in operation, substantially as described.

3. In a swaging machine, the combination of the rotating head, the beaters, the swaging dies, and the engaging-blocks with the toggle-links, provided at their central joints with 15 the cylindrical pin, and the washers which engage with the sides of the toggle-links, substantially as described.

ANTOINE J. LANGEIER.
